UNITED STATES PATENT OFFICE.

HERMAN HAGER, OF DETROIT, MICHIGAN.

AUTOMOBILE RADIATOR.

1,000,259.

Specification of Letters Patent. Patented Aug. 8, 1911.

Application filed November 7, 1910. Serial No. 591,139.

To all whom it may concern:

Be it known that I, HERMAN HAGER, citizen of the United States, residing at Detroit, county of Wayne, State of Michigan, have invented a certain new and useful Improvement in Automobile Radiators, and declare the following to be a full, clear, and exact description of the same, such as will enable others skilled in the art to which it pertains to make and use the same, reference being had to the accompanying drawings, which form a part of this specification.

My invention relates to an improvement in radiators for automobiles, shown in the accompanying drawings and more particularly set forth in the following specification and claims.

The object of this invention is an improvement in the general construction of appliances of this character whereby the radiating surface may be materially enlarged without increasing the width of the radiator itself as ordinarily constructed. In the present arrangement all air currents entering between the water tubes are forced to travel in a zigzag manner on each side of the entire bank of tubes from bottom to top thereof, thereby increasing the general efficiency of the device while the cost of manufacture over radiators now in use is greatly reduced.

Another feature of the invention consists in providing means to cut off the in-flow of air currents between the tubes, frequently found desirable during a severe cold or winter season to prevent freezing.

Other advantages and improvements will hereafter appear.

In the drawings accompanying this specification: Figure 1 is a front elevation with parts in section,—the arrows indicating the water circulation. Fig. 2 is a vertical cross-sectional view on line 2—2 of Fig. 1. Fig. 3 is a horizontal sectional view on line 3—3 of Fig. 1. Fig. 4 is a horizontal sectional view on line 4—4 of Fig. 1. Fig. 5 is a detail sectional view on line 5—5 of Fig. 1.

Referring now to the letters of reference placed upon the drawings:—A is the outer wall of the radiator, B a projecting nipple with which the water circulating pipe leading to the engine (not shown) is connected. B' is a similar nipple connected with the water circulating pipe, through which the water is returned to the radiator.

C are a plurality of zigzag or corrugated tubes relatively flat supported in end walls D, D, in turn spaced from the outer wall or jacket of the radiator,—the ends of the tubes being open as indicated at d in Fig. 4 to communicate with the chambers E, E, formed by the walls A, D, J, and K, of the radiator. The chambers E are sub-divided by partition walls or baffle plates e thus providing an enforced circulation of the water from one side of the radiator to the other through the tubes C as indicated by the arrows in Figs. 2 and 4 of the drawings.

F is a damper hinged at f having a suitable spring latch f' adapted to secure the damper against being accidentally opened when closed.

G is the usual inlet cap through which water is introduced into the radiator, and H is the water overflow pipe.

e' indicates outlets in the chambers E to insure the complete draining of the radiator in cold weather.

Having indicated the several parts by reference letters, the construction and operation of the appliance will be readily understood.

Assuming that the radiator has been properly installed and charged with water, the incoming air entering at I, will pass upwardly in a zigzag manner between each of the flattened corrugated tubes, being drawn out at I' by a fan (not shown), while the water in the tubes will be forced by the baffle plates e to circulate in the direction indicated by the arrows, passing out to the engine through the nipple B, then returning to the radiator through the nipple B'.

It will be understood that by corrugating the tubes their strength is greatly increased without materially enlarging the space occupied by them:—while the direction of the air current is continually changing as they are through the zigzag formation of the tubes, insures a much more rapid cooling of the tubes than would otherwise be obtained.

Having thus described my invention, what I claim is:—

1. In an apparatus of the class described, a plurality of relatively broad, flat, vertically arranged, horizontal tubes spaced apart for the passage of air between them, suitable headers or chambers with which said tubes communicate, baffle plates supported in said headers to insure a circulation of

water through each of said tubes, and means adapted to connect with the circulating-pipes leading to and from the engine.

2. In an apparatus of the class described, 5 a plurality of relatively broad, flat, vertically arranged, horizontal corrugated tubes spaced apart for the passage of air between them, suitable headers or chambers with which said tubes communicate, baffle plates 10 dividing said headers adapted to insure a circulation of water through all of said tubes, and suitable nipples by means of which communication may be established with the circulating pipes leading to and 15 from the engine.

3. In an apparatus of the class described, 20 a plurality of relatively broad, flat, vertically arranged corrugated horizontal tubes spaced apart for the passage of air between them, suitable headers or chambers with which said tubes communicate, baffle plates 25 dividing said headers adapted to insure a circulation of water through all of said tubes, outlets for draining said chambers, and suitable nipples by means of which communication may be established with the circulating pipes leading to and from the engine.

4. In an apparatus of the class described, 30 an outer annular water chamber, a plurality of relatively broad, flat, vertically arranged, horizontal corrugated water tubes spaced apart for the passage of air, bridging the 35 annular opening of said chamber and communicating therewith, a plurality of baffle plates dividing said annular chamber adapted to insure the circulation of water through each of said tubes, means for admitting air 40 between each of the tubes, and means whereby a water circulation may be established with the water circulating pipe leading to and from the engine.

5. In an apparatus of the class described, 45 an outer annular water chamber, a plurality

of relatively broad flat corrugated water 45 tubes spaced apart for the passage of air, bridging the annular opening of said chamber and communicating therewith, a plurality of baffle plates dividing said annular chamber adapted to insure the circulation 50 of water through each of said tubes, means whereby air may be admitted between each of the tubes, a damper for controlling the admission of air between the tubes, and means for establishing a water connection 55 with the water circulating pipe leading to and from the engine.

6. In an apparatus of the class described, 60 an annular header, a plurality of relatively broad, flat, vertically arranged horizontal 65 tubes spaced apart for the passage of air between them and bridging the space between the walls of the header, baffle plates dividing said header to insure a circulation of water through all of the tubes, and nipples connected with the header by which communication may be established with the circulating pipes leading to and from the engine.

7. In an apparatus of the class described, 70 an annular header, a plurality of relatively broad, flat, vertically arranged, horizontal zig-zag tubes spaced apart for the passage 75 of air between them and bridging the space between the walls of the header, baffle plates dividing said header to insure a circulation of water through all of the tubes, and nipples connected with the header by which communication may be established with the 80 circulating pipes leading to and from the engine.

In testimony whereof, I sign this specification in the presence of two witnesses.

HERMAN HAGER.
